AUDIO-VISUAL TEACHING DESK

Kurt H. Hoppmann, Falls Church, and Victor L. Reddle,
McLean, Va., assignors to Staples-Hoppmann, Inc.,
Alexandria, Va., a corporation of Virginia

Filed Sept. 24, 1962, Ser. No. 71,825

Term of patent 14 years

(Cl. D33—7)

FIG. 1

FIG. 1 is a front perspective view of an audio-visual teaching desk showing our design, the door along the desk top thereof being in open position;

FIG. 2 is a rear elevation thereof with the console top door in closed position;

FIG. 3 is a side elevation thereof; and

FIG. 4 is a sectional view thereof taken along section line 4—4 of FIG. 2.

We claim:

The ornamental design for an audio-visual teaching desk, as shown.
